CARPET LAYING INSTRUCTION APPARATUS

John R. Pollard, Amsterdam, N. Y., assignor to
 Mohawk Carpet Mills, Inc., Amsterdam, N. Y.,
 a corporation of New York

Application August 1, 1947, Serial No. 765,495

7 Claims. (Cl. 35—53)

1

This invention relates to apparatus for giving instruction and is concerned more particularly with a novel apparatus, by which instruction may be given in the laying of carpet, with or without underlying cushioning material. The use of the apparatus enables an instructor to demonstrate how to lay carpet to cover areas of regular or irregular outline, the demonstration involving cutting the carpet to fit the outline, stretching the carpet taut, and securing it in place along the boundary of the area. After such a demonstration, the apparatus may be used by the pupils for practice, and the apparatus makes it possible to vary the shape of the area to be carpeted, so that different conditions encountered in carpet laying in the field may be simulated. Although actual carpet and cushioning material are used for both instruction and practice, only small amounts of the carpet and cushioning material are consumed in a single laying operation, so that the apparatus may be utilized for instruction and practice at little expense.

The preferred form of the apparatus includes a platform structure having a flat top, above which a wall rises at one end. The structure includes supports, preferably mounted below the top, for supplies of carpet and cushioning material and, when the supplies, usually rolls, are mounted below the top, the carpet and material are led upwardly through openings lying remote from the wall and extending parallel thereto. Means are provided for varying the outline of the end of the top adjacent the wall and such means may take the form of blocks, which can be removably secured to the top along the wall and used in different arrangements to give that end of the top an irregular boundary. The apparatus includes means adjacent the supplies of cushioning material and carpet for gripping the latter along lines parallel to the wall and adjacent the supplies and means may also be provided for securing the free end of the carpet and cushioning material, after they have been stretched taut, along the boundary of the top adjacent the wall. The back portion of the top serves as a floor, on which a speaker may stand to explain a demonstration being made or to give instruction to a pupil, who is practicing. To assist the instructor, the platform structure is provided with a support rising above the top of the platform at the rear and carrying a projection screen, upon which instructions may be projected by means of slides.

For a better understanding of the invention, 55

reference may be made to the accompanying drawings, in which

Fig. 1 is a view of the apparatus in perspective with parts broken away;

Fig. 2 is a view in perspective of different blocks used with the apparatus;

Fig. 3 is a central transverse sectional view through the apparatus;

Fig. 4 is a longitudinal sectional view through the apparatus; and

Fig. 5 is a sectional view on the line 5—5 of Fig. 4.

The apparatus in the form shown comprises a platform structure 10, which includes a top 11 of floor boards laid edge to edge and supported by a framework, which includes upper and lower horizontal members 12, 13, and upright 14. The structure is rectangular and is provided with casters 15 attached to the framework adjacent the corners, so that the structure may be readily moved about.

A wall 16 rises from the top of the platform at one end and may consist of horizontal and vertical boards connected together and supported by brackets 17. Adjacent the wall, the top of the platform is provided with a number of openings 18, which may receive pins 19 on blocks 20 provided with handles 21. The blocks may be boxes of light construction and a number of blocks of different shape are provided with the apparatus so that, by mounting them on the top of the platform, the boundary of the top adjacent the wall may be made irregular to simulate the wall of a room having, for example, a fireplace, a door, or other like structural feature.

A supply of cushioning material in the form of a roll 22 is mounted beneath the top of the platform on rollers 23 supported in vertical plates 24 attached to the horizontal bars 13 of the framework. The cushioning material is led upwardly from the roll and passed through an opening 25 in the top of the platform. An inclined bar 26 is attached to the underside of the

platform along one side of the opening, the bar being braced by a second bar 27. A roller 28 is mounted eccentrically in suitable supports secured to the upper horizontal members 12 of the structure and lies adjacent bar 26. The shaft

29 of the roller extends out beyond the edge of the top and is provided with a crank 30, by which the roller may be rotated to move it close to bar 26.

A supply of carpet in the form of a roll 31 is mounted on rollers 32 supported for rotation in

plates 33 attached to frame members 13 and lies beneath an opening 34 through the top of the platform. At one side of the opening, a block 35 with an inclined face is secured to the underside of the platform and, on the other side of the opening, a block 36 is mounted for movement in guides 37. Block 36 has an inclined forward face provided with pins and the block is movable toward and away from block 35 by means of a shaft 38 having an arm 39 attached to block 36 by a link 40. The shaft is mounted in suitable bearings and projects out beyond the edge of the platform. At its outer end, it carries a crank 41, by which the shaft may be turned to move the block toward or away from the stationary block 35. A wall 42 rises from the platform along one edge of opening 34 but may be omitted, if desired.

The carpet and cushioning material employed with the apparatus are of less width than the width at the top of the platform and the rear portion 43 of the platform serves as a floor, on which a speaker may stand. A support 44 is mounted detachably on the platform structure along the rear edge of floor 43 and is provided with a screen 45. A projector 46 is mounted on a support 47 to the rear of the screen and a hood 48 leads from the front of the projector to the rear of support 44 around screen 45. Support 47 may be formed with a platform 49, on which the operator of the projector may stand. The hood 48 is preferably detachably secured to the rear of support 44 and also to a bracket 50 on support 49.

In the use of the apparatus for the purpose of demonstrating the laying of carpet to cover an area with an irregular boundary, the instructor places one or more of the blocks 20 with their pins in appropriate openings 13 in the top of the platform adjacent the wall. He then releases the gripping means for the cushioning material and carpet and pulls from the supplies suitable lengths which, when stretched taut, will reach to the wall. The gripping means are then operated to clamp the carpet and cushioning material and the free ends of the carpet and cushioning material are cut so that they will fit smoothly along the sides of the blocks and the exposed portion of the wall. The instructor then stretches the carpet and cushioning material taut by the usual tools and secures the carpet and cushioning material in place along the irregular boundary of the top. For this purpose, he may use tacks driven through the carpet and cushioning material and into the top of the platform or, if preferred, he may use fastening devices, consisting of a strip of wood 51 provided with inclined nails 52 projecting upwardly therefrom. When such fastening devices are used, the strips are cut and nailed in place along the irregular boundary of the top before the carpet and cushioning material are stretched.

During the actual laying operation, the speaker may stand on floor 43 and may explain what the demonstrator is doing. Also, slides may be projected on screen 45, so that the spectators may both see the demonstration and read an explanation carried by the slides.

When the demonstration has been completed, the carpet and cushioning material are detached from the top of the platform and the free ends thereof are trimmed off, so that the ends are square. Thereafter, a different arrangement of boxes may be used to present another problem or the carpet may be merely secured in place along

the wall. Ordinarily, only small amounts of carpet and cushioning material are consumed in a single laying operation and the supplies of carpet and cushioning material will last for a considerable period of time. When the supplies have nearly run out, the ends of the original supplies can be connected to new supplies and the use of the apparatus continued as before.

The support 44 carrying screen 45 is demountable from the platform and the hood 48 may be made collapsible. The entire apparatus may, accordingly, be stacked in a relatively small space, so that it can be easily transported from one point to another.

15 I claim:

1. A carpet laying instruction apparatus, which comprises a platform structure having a flat top and a wall rising above the top at one end, a support beneath the top and remote from said wall for holding a supply of carpet, the top having an opening parallel to said wall, through which the carpet can be drawn from the supply to overlie the top, and means beneath the top and adjacent the support for gripping carpet drawn from the supply.

2. A carpet laying instruction apparatus, which comprises a platform structure having a flat top and a wall rising above the top at one end, supports beneath the top at the other end of the structure for supplies of carpet and cushioning material, the support for the supply of cushioning material lying nearer said wall and the top having a pair of openings parallel to said wall, through which the cushioning material and carpet, respectively, can be drawn from the supplies over the top, and separate means adjacent the individual supports for gripping carpet and cushioning material drawn from the supplies.

3. A carpet laying instruction apparatus, which comprises a platform structure having a flat top and a wall rising above the top at one end, a block mounted on the top adjacent the wall and with the latter defining an irregular boundary for the top, a support for a supply of carpet beneath the top and at the other end of the structure, the top having an opening through which carpet from the supply can be drawn to overlie the wall, and means adjacent the support for gripping carpet drawn from the supply.

4. A carpet laying instruction apparatus, which comprises a platform structure having a flat top and a wall rising above the top at one end, a block mounted on the top adjacent the wall and with the latter defining an irregular boundary for the top, supports on the structure beneath the top for supplies of carpet and cushioning material, the carpet and cushioning material being of substantially the same width and of less width than the top, the top having transverse openings parallel to the wall and remote therefrom, through which the carpet and cushioning material may pass, means adjacent the openings for gripping the carpet and cushioning material, and means on the top along said boundary for holding the free ends of carpet and cushioning material, which have been stretched taut from their gripping means.

5. A carpet laying instruction apparatus, which comprises a platform structure having a flat top and a wall rising above the top at one end and extending partway across the top, a support for a supply of carpet beneath the top and at the other end of the structure, the carpet having a width approximately equal to the length of

the wall, the top having an opening, through which carpet from the supply can be drawn over the top, the opening being parallel to the wall and having its ends aligned with those of the wall, and means on the structure adjacent the support for gripping carpet drawn from the supply along a line parallel with the wall.

6. A carpet laying instruction apparatus, which comprises a platform structure having a flat top and a wall rising above the top at one end, a block mounted on the top adjacent the wall and with the latter defining an irregular boundary for the top, a support for a supply of carpet at the other end of the structure, and means adjacent the support for gripping carpet drawn from the supply along a line parallel to the wall.

7. A carpet laying instruction apparatus, which comprises a platform structure having a flat top and a wall rising above the top at one end, a

15

10

20

block mounted on the top adjacent the wall and with the latter defining an irregular boundary for the top, supports on the structure adjacent the other end for supplies of carpet and cushioning material, and means adjacent the supports for gripping the carpet and cushioning material drawn from the supplies thereof along lines parallel to the wall.
